FLOW METER OR THE LIKE

Russell G. Hunt, 1308 Shelley St., Santa Ana, Calif.

Filed Sept. 8, 1964, Ser. No. 81,617

Term of patent 3½ years

(Cl. D52—6)

Fig. 1

Fig. 2

Fig. 3

Fig. 4

FIG. 1 is a front elevational view of a flow meter or the like showing my new design, the rear being identical thereto;

FIG. 2 is a cross-sectional view thereof taken on line 2—2 of FIG. 1;

FIG. 3 is an end elevational view of the indicator card and pointer of the flow meter;

FIG. 4 is a perspective view thereof.

The broken-line showing of end flanges, gasket and tie rods in FIGS. 1 and 2 is for illustrative purposes only.

I claim:

The ornamental design for a flow meter or the like, substantially as shown and described.
